UNITED STATES PATENT OFFICE.

BEN A. BALL, OF PAWTUCKET, RHODE ISLAND, ASSIGNOR TO AMERICAN TEXTILE CO., INC., OF PAWTUCKET, RHODE ISLAND, A CORPORATION OF RHODE ISLAND.

DESIGN FOR LACE.

Application filed October 27, 1927. Serial No. 23,902. Term of patent 3½ years.

To all whom it may concern:

Be it known that I, BEN A. BALL, a citizen of the United States, and a resident of Pawtucket, in the county of Providence and State of Rhode Island, have invented the new, original, and ornamental Design for Lace, of which the following is a specification, reference being had to the accompanying drawing forming part thereof.

In the drawing—

The figure is an elevation of lace, showing my new design.

I claim:

The ornamental design for lace, as shown. Signed at Pawtucket in the county of Providence, and State of Rhode Island this 25th day of October, A. D. 1927.

BEN A. BALL.
